UNITED STATES PATENT OFFICE.

THOMAS ALBERT SWEET, OF PASO ROBLES, CALIFORNIA.

WINDOW-SASH.

SPECIFICATION forming part of Letters Patent No. 357,246, dated February 8, 1887.

Application filed September 25, 1886. Serial No. 214,541. (No model.)

To all whom it may concern:

Be it known that I, THOMAS ALBERT SWEET, a citizen of the United States, residing at Paso Robles, in the county of San Luis Obispo and State of California, have invented a new and useful Improvement in Window-Sashes, of which the following is a specification.

My invention relates to improvements in windows; and it consists in the peculiar combination and novel construction and arrangement of the various parts for service, substantially as hereinafter fully described, and particularly pointed out in the claim.

The object of my invention is to provide an improved window-sash which can be turned completely around, so that ready access thereto can be had to readily wash or clean both sides of the glass or pane therein.

A further object of my invention is to provide an improved sash which shall be free from shrinkage or warping, which is liable to cause the sash to bind, and to provide novel means for securing the pane or glass in the sash.

In the drawings hereto annexed, which illustrate a window embodying my invention, Figure 1 is a side elevation showing two of the sashes thereof closed and two of them opened. Fig. 2 is an enlarged transverse sectional view on the line *x x* of Fig. 1. Fig. 3 is a detached view of one of the sashes; and Fig. 4 is a horizontal sectional view, on an enlarged scale, through one of the sashes.

Referring to the drawings, in which like letters of reference denote corresponding parts in all the figures, A designates the inclosing or main frame of my improved window, which is rigidly affixed in the wall of the building and divided into two halves or sections by a transverse timber, *a*, which is rigidly secured or affixed in place.

B designates the interior metallic frames, which are each cast in a single piece of metal and are rigidly fixed within each half or section of the main frame by suitable screws or other devices, the sides of the supplemental metallic frames being arranged flush with the sides of the main frame, as clearly shown.

C are the swinging sashes, which are arranged in vertical positions and are free to turn or rotate horizontally on vertical central pivots, D, which are fixed in the sashes and journaled in the supplemental metallic frames, as shown.

If preferred, the vertical central pivots or trunnions of the horizontally-swinging sashes may be extended through the supplemental frame B into the main frame A, as shown in dotted lines in Fig. 1. Two of these sashes are provided for each of the supplemental metallic frames, and they are adapted to align with one another, as shown in the lower portion of Fig. 60 1, or to be arranged at any angle, as shown in the upper part of the same figure.

Each sash consists of two frames or sections, E and F, which are each cast in a single piece of metal and of substantially the same size and shape. These frames or sections are placed together, so that their several side edges are in line with each other, and they are then secured or connected together by means of screws *e*, or other suitable devices. The sides of the outer or exposed section or frame F of the sash are beveled or inclined, as shown, to impart a neat finish or appearance thereto, and the sides of the inner frame or sash are likewise beveled for a like purpose, and have enlarged ears or lugs *f*, through which are formed the transverse openings for the passage of the securing-screws *e*, as is obvious.

The inner opposing edges of the frames or sections of each sash are provided with recesses or grooves, which are lined with elastic packing-strips *g*, of rubber, leather, or other suitable material, and in these grooves or recesses of the frames or sections of the sash are fitted the edges of the pane of glass H. The sections are securely clamped and held together by the screws, so that they press the elastic packing-strips very firmly upon the edges of the pane of glass, and thus more securely hold and retain the pane in place and make or render the sash water and dust proof. All water, dust, dirt, snow, &c., is very effectually prevented from passing through the sash, and the cold is also more effectually excluded. As the sash-frames are made of metal, they are unaffected by the action of the elements or weather thereon, and therefore not liable to shrinkage. The frames are made of very light castings, so that they can be revolved very easily and with a minimum exertion of force on the part of the operator.

The trunnions or journals of the sashes are cast or formed integral with one of the frames, and when the frames are adjusted and secured together the pivots are arranged

at the center thereof, so that the sash will swing or revolve very evenly.

Each sash is provided at its outer side nearest the metallic supplemental frame with a 5 pivoted button or other preferable form of locking device, G, which can be operated very easily to prevent the sash from movement.

The operation of my invention will be very readily understood. When it is desired to 10 open the window to admit air to the apartment, or for other purposes, the turn-button or other locking device is operated to release the sash, which can then be very freely turned or rotated by pushing upon the same to one 15 side of the vertical center thereof, thus swinging the sash in a horizontal plane. The sash can be freely revolved entirely around on its vertical pivots or trunnions, to expose either side thereof, and both sides of the pane of glass 20 therein can be very readily washed or cleansed with great facility.

The device is simple and durable in construction, effective and reliable in operation, and cheap and inexpensive of manufacture.

25 Slight changes can be made in the form and proportion of parts without departing from the principle of my invention.

The inner opposing sides of two adjacent sashes which are journaled in one of the sup-

plemental frames are beveled or inclined to 30 adapt the same to more readily swing and clear one another without interfering with each other, and also to provide a close joint between the said sides of the sashes.

Having thus fully described my invention, 35 what I claim as new, and desire to secure by Letters Patent, is—

The combination, with the inclosing main frame, of the interior metallic frame or frames, B, and the swinging sashes turning on the vertical pivots and consisting each of the two metallic frames of uniform size and shape, having the grooves formed in their opposing faces, and one of said frames having formed integral with it the vertical pivots or trunnions, the 40 elastic packing-strips fitted in the said grooves, the glass fitted at its edges in the grooves between the packing-strips, and the screws 45 detachably securing the metallic sections or frames together.

50 In testimony that I claim the foregoing as my own I have hereto affixed my signature in presence of two witnesses.

THOMAS ALBERT SWEET.
